(57) **CLAIM**

The ornamental design for a combination volute and motor mount for a pump as shown and described.

DESCRIPTION

FIG. 1 is a front, top perspective view of a combination volute and motor mount for a pump according to the present invention with a motor depicted in dashed lines mounted to the motor mount;

FIG. 2 is a front, top perspective view of the combination volute and motor mount for a pump as shown in FIG. 1;

FIG. 3 is a front, bottom perspective view thereof;

FIG. 4 is a rear, top perspective view thereof;

FIG. 5 is a rear, bottom perspective view thereof;

FIG. 6 is a front elevational view thereof;

FIG. 7 is a rear elevational view thereof;

FIG. 8 is a left side elevational view thereof;

FIG. 9 is a right side elevational view thereof;

FIG. 10 is a top plan view thereof; and,

FIG. 11 is a bottom plan view thereof.

The broken lines in FIG. 1 depicting the motor mounted on the motor mount of the combination volute and motor mount for a pump are included to illustrate environmental subject matter that forms no part of the claimed design. All other broken lines in FIGS. 1-11 are for the purpose of illustrating portions of the combination volute and motor mount for a pump that form no part of the claimed design.

1 Claim, 6 Drawing Sheets
